CASING FOR A WRITING INSTRUMENT

Alan E. Sherman, St. Louis County, Mo., assignor to
Penn Corporation, Princeton, N.J., a corporation of
Delaware

Filed June 13, 1969, Ser. No. 17,701

Term of patent 14 years

Int. Cl. D19—06

U.S. Cl. D74—17

FIG. 1

FIG. 2

FIG. 3

FIG. 4

FIG. 1 is a plan view of a casing for a writing instrument showing my new design;

FIG. 2 is another plan view thereof as it appears rotated 90° from FIG. 1;

FIG. 3 is an end view as seen from the left of FIG. 2; and

FIG. 4 is an end view as seen from the right of FIG. 2.

The design is for a tapered casing having an elongated clip adjacent its narrow end. The casing is substantially free from outwardly projecting protuberances adjacent its enlarged end.

I claim:

The ornamental design for a casing for a writing instrument, as shown and described.
